SCREW DRIVER

Filed Sept. 3, 1929

O. W. POTTS.
INVENTOR.

BY *Lacey, Lacey*
ATTORNEY.s

UNITED STATES PATENT OFFICE

OLLIE W. POTTS, OF NEWPORT, KENTUCKY

SCREW DRIVER

Application filed September 3, 1929. Serial No. 390,098.

This invention relates to tools and more particularly to a screw-driver. One object of the invention is to provide the screw-driver with a handle so mounted that it may be disposed either longitudinally or transversely of the shank and blade and thereby allow the screw-driver to be used in the usual manner with the handle extended longitudinally of the shank or adjusted to dispose the handle 10 transversely of the shank in order to allow a firmer grip to be obtained and greater leverage exerted in case it is difficult to loosen or fully tighten a screw.

Another object of the invention is to provide the handle with jaws adapted to firmly grip the shank of the screw-driver when the handle is disposed longitudinally thereof but at the same time allow the jaws to be easily forced out of gripping engagement with the 20 shank when it is desired to move the handle to a position transversely of the shank.

Another object of the invention is to so form the handle that it may be firmly gripped and pressure exerted when it is disposed longitudinally of the shank without injuring a person's hand.

The invention is illustrated in the accompanying drawings wherein

Figure 1 is a view in side elevation showing the handle disposed longitudinally of the shank,

Figure 2 is a similar view showing the handle disposed transversely of the shank, and

Figure 3 is a sectional view taken along the 35 line 3-3 of Figure 1.

This improved screw-driver includes a shank 1 formed of steel or other strong metal. This shank may be of any length desired and is rectangular in cross-section for practically its entire length. The forward end of the shank is flattened from opposite sides to form a blade 2 and its rear end portion is also flattened from opposite sides as shown at 3. It will thus be seen that the shank and blade 40 consist of a single bar of metal and that since it is rectangular in cross-section it will be provided with opposed corners, as shown in Figure 3.

The handle which is pivoted to the flattened 45 rear end of the shank is provided with a

core or filler 4 which may be formed of wood, metal, or a suitable composition. This core has a rounded rear end as shown in Figure 1 and tapers forwardly and also has its side faces curved longitudinally and transversely as shown in Figures 2 and 3 so that it may be firmly gripped without cutting into a person's hand. A strip of flat metal is bent intermediate its length to form a binding 5 having an arcuate portion 5^a extending about 55 the rear end of the core and side portions 5^b extending in converging relation to each other and in front of the core are bent to form parallel portions 6 which fit flat against opposed faces of the flat rear end portion 3 of the shank where they are pivotally secured by a rivet or equivalent fastener 7. The end portions of the strip form arms 8 extending 60 in diverging relation to the shank and constituting shoulders having approximately the same shape as the converging portions 5^a after 65 which the ends of the strip are bent towards each other to form converging jaws 9. These jaws normally terminate close to each other and at their ends are notched or recessed to 70 form seats 9' adapted to receive the opposed shoulders of the shank. 75

When the screw-driver is in use the handle will usually be disposed longitudinally of the shank and in view of the shape of the handle it may be firmly gripped with a thumb and finger bearing against the arms 8 and pressure applied without injuring a person's hand. The jaws very firmly grip the shank and since corners of the shank are received 80 in the notches or recesses 9 the handle will not be liable to accidentally move out of its position shown in Figure 1. If it is found that a screw cannot be easily loosened or fully tightened the handle may be swung 85 about the pin 7 until it assumes the position shown in Figure 2. It can then be used with either one or both hands gripping the handle and a leverage exerted not obtainable when the handle is in the position shown in Figure 90 1. If so desired the core 4 may be omitted and the U-shaped portion of the binding used 95 as a handle.

Having thus described the invention, I claim:

A screw driver comprising a bit having a shank provided with a blade at its outer end and having longitudinally extending opposed corners, the rear end of the shank being flattened, a stiff elastic looped strip forming a handle having an arcuate end and side portions converging forwardly, said strip having parallel portions bearing against opposed faces of the flattened rear portion of said shank and continuing in arms diverging forwardly from the parallel portions to form shoulders of approximately the same slope as the handle, then converging and terminating in jaws opposing each other and adapted to grip the shank, said jaws being formed with notches to receive the corners of the shank, and a pivot passed through the parallel portions of the handle and flattened rear end of the shank to pivotally mount the shank.

In testimony whereof I affix my signature.
OLLIE W. POTTS.
